BAG OPENER

Harold V. Kindseth, Minneapolis, Minn., assignor
to Bemis Bro. Bag Company, Minneapolis,
Minn., a corporation of Missouri

Application May 8, 1948, Serial No. 25,875

4 Claims. (Cl. 226—59)

1

This invention relates to a new and improved bag opener particularly well suited for opening small "cellophane" bags.

Heretofore, when filling small flexible walled bags or containers, which are normally in a flattened condition prior to filling, to facilitate storage, difficulty has frequently been experienced when inserting the contents into the bags, to fully expand the bag walls and particularly the bottom wall portions of the bag so that the bag, when filled and sealed, will present a neat and pleasing appearance to the eye.

It is common to dispense numerous commodities such as peanuts, nuts, candy and the like, in small transparent "cellophane bags," the walls of which inherently are rather difficult to fully expand when inserting the contents into the bag bodies. This results, first, because of the particular manner in which the bottom portions of the bag body walls are folded, when the bag is in a flattened condition, whereby the gussets thereof at the bottom of the bag may not completely unfold because of portions of the contents becoming wedged between the plies or walls of the gussets; and, secondly, because the weight of the contents of the bag body may not be sufficient to cause the lower portions of the bag body walls to become fully expanded to a desired squared condition during the filling operation.

To overcome this difficulty, it has been necessary to insert some instrument or device into the bag body to expand its walls, or at least partially expand them, and at the present time it has been quite common for an operator filling such bags to insert one or more fingers into each bag to expand its walls prior to filling the bag. This requires time and obviously tends to retard the filling operation of the bags. Furthermore, it does not assure that the bottoms of the filled bags will be completely expanded and squared, so that when the bags are filled, the bag bottoms may not be sufficiently squared to permit the filled bags to be placed upon their bottoms in an upright position.

One of the important objects of the present invention, therefore, is to provide a bag opener particularly adapted for opening small bags, which comprises an elongated member over which the empty bags may readily be fitted when in normal flattened condition, and said member being operable upon receiving the empty bag to expand its walls to their normal squared positions, including the squaring of the bag bottom, after which the contents may be delivered into the bag and compacted therein to provide a package

which will present a very neat and pleasing appearance to the eye.

A further object is to provide a simple, inexpensive bag opener which may readily be mounted upon a suitable table and comprises a member over which the empty bag is fitted and which, when actuated by depression of a simple foot pedal, completely and fully expands the bag walls and simultaneously squares its bottom after which a charge may be delivered into the expanded bag body and its open top closed and sealed.

A further object is to provide a combination bag opener or expander and a filling hopper having a funnel-like discharge opening adapted to deliver material into the open mouth of the bag when the bag opener has been actuated to expand the walls of the empty bag.

Other objects of the invention reside in the simplified construction of the supporting frame of the opener; in the construction of the bag wall expanding device which consists of two hinged members normally folded into flatwise relation with their supporting plate and having means for outwardly swinging them to expand the bag walls and simultaneously square the bag bottom; in the arrangement of the hopper in the upper portion of the device and the provision of a glass panel between the bottom of the hopper and the top of the empty bag, whereby the operator may readily note the contents as they discharge from the hopper into the bag body; and in the simple construction of the operating means for the wing members whereby all of the parts thereof are exposed to view and are readily accessible in the event that they may require repairs or adjustment.

These and other objects of the invention and the means for their attainment will be more apparent from the following description taken in connection with the accompanying drawings.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a side elevation of the novel bag opener herein disclosed, showing it mounted upon a table and an empty bag fitted over the bag opening member thereof;

Figure 2 is a front view of the bag opener showing the wing members for expanding the bag body walls in inoperative positions;

2

Figure 3 is a vertical sectional view substantially on the line 3-3 of Figure 2, showing the simple construction of the apparatus;

Figure 4 is a fragmentary view on a larger scale, showing the driving connections between the operating member and the two wing members;

Figure 5 is a cross-sectional view on the line 5-5 of Figure 3 on a larger scale, showing the transparent panel positioned above the open bag top to prevent portions of the material being packaged in the bags from discharging onto the floor during the filling operation.

Figure 6 is a detail sectional view on the line 6-6 of Figure 1, showing an empty bag positioned over the wing members with the bag walls partially collapsed;

Figure 7 is a view similar to Figure 6, but showing the wing members actuated to fully expand the bag walls;

Figure 8 is a detail sectional view on the line 8-8 of Figure 4;

Figure 9 is a fragmentary view showing the bag wall opening means in its normal collapsed condition with the transparent plate positioned thereover; and

Figure 10 is a perspective view of a bag showing the squared formation of its bottom resulting from having its walls expanded on the novel device herein disclosed, and whereby the filled bag may be placed upon its bottom, when filled.

The novel bag opener or expander herein disclosed is shown comprising a frame, preferably of metal, generally designated by the numeral 2. It is shown comprising side plates 3 and 4 secured together in spaced relation by a suitable cross member 5 at the rear of the machine, and having the bottom edges of its side walls 3 and 4 secured to a suitable base plate 6, shown in Figures 1, 2 and 3. The plate 5 may be secured to the rear edges of the side plates 3 and 4 by such means as welding, and the lower edges of the side walls may be similarly secured to the bottom plate 6. Suitable apertures 7 may be provided in the base plate 6 whereby the device may readily be secured to a table top, as indicated in Figure 1. The lower front portion of the frame 2 is preferably open, as shown in the drawings, whereby the frame 2 may readily be clamped to a table top by a conventional C-clamp, as will readily be understood by reference to Figures 1 and 3.

Interposed between the side walls 3 and 4 within the upper portion of the frame 2 is an inclined plate 8, the opposite edges of which are suitably secured to the walls 3 and 4, whereby the plate 8 securely ties together the upper portions of the frame walls 3 and 4, and, in addition, provides a support for the bag wall opening means, next to be described.

The bag wall opening or expanding means is generally indicated by the numeral 9, and is shown comprising an inclined plate 11 having its upper portion secured to the inclined plate or wall member 8 of the supporting frame 2 by such means as bolts 12, shown in Figure 3. Secured to the plate 11 are opposed elongated hinge members 13 and 14 each comprising a portion 15 adapted to be secured to the plate 11, and suitable wing members 16 being secured to longitudinally extending hinge shafts 17, whereby when the shafts 17 are relatively rotated, the wing members 16 are swung inwardly or outwardly, as will subsequently be described.

The wing members 16 are secured to the hinge or wing members 13 by such means as welding,

as will be understood by reference to Figures 5 and 6, and are of such size that when swung outwardly to the positions shown in Figure 5, the bag body walls will be expanded to their maximum fullness, as clearly illustrated in Figures 5 and 7.

Suitable sheaves 19 are secured to the upper ends of the hinge shafts 17 at the rear of the supporting frame 2, and each has one end of a flexible element 21, such as light cable or cord, secured thereto, as indicated at 25 in Figure 4. A spring 22 has one end connected to the cord 21 and its opposite end is fixed to a portion of the supporting frame 2, as indicated at 23 in Figures 1 and 3, whereby a downward pull is constantly exerted on the flexible element 21 to rotate the wing elements 16 to their collapsed positions, shown in dotted lines in Figure 4 and in full lines in Figure 6.

Other cables 24 have their upper ends secured to the peripheries of the sheaves 19, as shown at 25, and have their lower ends connected to the upper end of a slide 26, mounted for vertical sliding movement in a guide 27 secured to the tie member 5 at the rear of the supporting frame 2. Secured to the lower end of the slide 26 is the upper end of a connection 28, the lower end of which may be connected to a suitable operating pedal 29 pivoted at 31, as shown in Figure 1. The cable portions or runs 24 pass over a horizontally disposed roller 30 at the rear of the apparatus, as shown in Figures 1 and 3.

To further extend the usefulness of the device a suitable hopper 32 is mounted in the upper portion of the frame 2 and has its opposed side walls welded to the upper horizontal edge portions 33 of the side walls 3 and 4 of the frame 2, as indicated at 34 in Figures 1 and 2. The hopper has a funnel-shaped discharge 35 positioned over the inclined plate 11 of the bag wall opening device 9, whereby when the wing members 16 are swung outwardly with their bag wall expanding positions, shown in Figures 5 and 7, material introduced in the hopper 32 may discharge onto the plate 11 of the member 9 between the upright wing members 16 and will flow downwardly thereon into the empty bag, as will readily be understood by reference to Figure 3.

The length of the bag wall expanding device 9 is such that when an empty bag is fitted thereto, as shown in Figures 1 and 3, the upper edges of the bag top walls will be spaced downwardly from the funnel-shaped discharge 35 of a hopper, and the gap provided between the edges of the bag walls and the bottom of the hopper discharge is closed at the top by a transparent panel 36, which may be suitably secured to a bracket 37 adjustably fixed to the front wall 38 of the hopper by a fastening element 39.

In operation, a flat, empty bag is fitted over the collapsed bag wall expanding device 9, as shown in Figure 1; the operator pulling the bag upwardly onto the member 9 by partially opening the mouth of the bag and grasping the top wall portions with the fingers of one hand. If desired, the operator may fit the empty bag onto the member 9 by grasping the bag adjacent to its bottom. When the empty bag has been pulled onto the member 9, as shown in Figure 1, the operator depresses the foot pedal 29 which, through its connections with the shafts 17 of the hinge members 13 and 14, will cause the wing members 16 to swing outwardly against the bag walls and thereby expand them into rectangular

formation in cross section, as illustrated in Figures 5 and 7.

Simultaneously, as the upright walls of the bag body are expanded, the bottom walls of the bag body will be squared to thereby completely condition the bag for receiving a charge of material. A charge may then be delivered into the bag from the hopper 32, after which the filled bag may readily be removed from the member 9 to have its open top closed and sealed in the usual manner.

By the use of the novel bag opener herein disclosed, each bag body may be quickly and completely expanded prior to receiving a charge, and as its bottom is also completely formed and squared, the filled bag will be self supporting when placed upon its bottom, as shown in Figure 10, and will present a very neat and attractive appearing article when its open top is subsequently closed and sealed.

While the invention has been found particularly useful in connection with bags of the smaller sizes, it is to be understood that it may conceivably be used for handling relatively larger bags by enlarging the machine to accommodate such bags. Its greatest use, however, has been found in the handling of small bag bodies, such as are used for dispensing nuts, candies, and other such commodities in small packages, and which bags are so small that it is difficult to insert a hand into the bags to fully expand the walls at the bottom of the bag.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. In an apparatus of the class described, a supporting frame, an elongated flat member secured at one end in said frame and having its opposite end portion projecting outwardly therefrom, wing elements hinged to the opposed side edges of the projecting end portion of said member substantially the length thereof, and normally folded inwardly over said member to permit an empty bag body to be fitted over said projecting end portion, and means connected to said pivoted elements for swinging them outwardly into substantially right angular positions relative to said member, and into engagement with opposed walls of the bag body to expand and square the walls of a bag positioned on said member, said wing elements engaging substantially the entire inner surfaces of said opposed walls.

2. In an apparatus of the class described, a supporting frame, an elongated plate-like member secured at one end in said frame with its opposite end portion projecting outwardly and downwardly therefrom, elongated wing elements

pivoted to the opposed side edges of the outwardly projecting end portion of said member, spring means normally retaining said wing elements in collapsed positions against said member to permit an empty bag body to be fitted over the projecting end portion thereof, means for outwardly swinging said wing elements against opposed walls of a bag body positioned on said member to expand and square the walls of the bag body, said 10 wing elements engaging substantially the entire inner surfaces of said opposed walls, means for introducing a charge of material into the bag body when thus expanded, and means for interconnecting said wing elements for simultaneous 15 operation in opposite directions.

3. In an apparatus according to claim 2, wherein the means for operating said wing elements includes a pair of spaced shafts each having a sheave secured to one end, and a flexible element having running connections with said sheaves and manually operable to actuate said wing elements to expand the walls of an empty bag fitted over the lower projecting end portion of said member.

4. In an apparatus of the class described, a supporting frame comprising spaced side walls, an elongated inclined member having one end interposed between the upper portions of said side walls and fixedly secured therebetween whereby the opposite end of said member projects outwardly and downwardly from the upper portion of said frame, wing elements pivoted to the opposed side edges of said elongated member and extending substantially the length thereof, means constantly urging said wing elements into collapsed positions over said member to permit an empty bag body to be fitted over the lower projecting end portion thereof, an operating mechanism for outwardly swinging said wing 30 elements into engagement with the opposed walls of an empty bag body fitted over the lower projecting end portion of said elongated member, thereby to expand and square the bag walls, a hopper in the upper portion of said frame having its discharge opening disposed over said elongated member, the upper portions of said wing elements and elongated member cooperating to provide a chute for conducting material from the hopper into the bag, when said wing elements 35 are in operative positions, and a transparent wall member positioned over said elongated member between the bag and said hopper thereby to prevent spillage of material when filling the bag, and through which the operator may view the 40 material entering the bag top.

HAROLD V. KINDSETH.
